UNITED STATES PATENT OFFICE.

LILLIAN A. EGGLESTON, OF CANYON, COLORADO.

DESIGN FOR A TAILOR'S SQUARE AND SCROLL.

SPECIFICATION forming part of Design No. 33,546, dated November 13, 1900.

Application filed October 6, 1900. Serial No. 32,308. Term of patent 14 years.

To all whom it may concern:

Be it known that I, LILLIAN A. EGGLESTON, a citizen of the United States, residing at Canyon city, in the county of Fremont and State 5 of Colorado, have invented and produced a new and original Design for a Tailor's Square and Scroll, of which the following is a specification.

This invention relates to a new and original 10 design for a tailor's square and scroll; and it has for its object to provide a design of this character which shall be both useful and ornamental.

The leading feature of the design resides 15 in a flat L-shaped body having separate arms of different lengths disposed at right angles to each other, said body being further provided with outer right-angularly-disposed straight edges and with a continuous compoundly-curved inner edge connecting the opposite terminals of the body at the outer ends of the arms, the said continuous curved inner edge having a concaved sharply-curved portion contiguous to the outer end of the 20 short arm, a long concaved curved portion extending nearly the full length of the long arm and merging into the aforesaid sharply-curved portion, and a convexed lobe adjoining the outer end of the long arm and merging into the 25 said long curve.

In the drawings, Figure 1 is an elevation of a tailor's square and scroll embodying the herein-described design. Fig. 2 is a cross-sectional view thereof on the line 2 2 of Fig. 1.

Referring particularly to the drawings, the 35 numeral 1 designates the complete body of the square and scroll. This body is of an L shape, the same having separate arms 2 and 3 of different lengths and which are disposed at right angles to each other. The said 40 body 1 is provided with outer right-angularly-disposed straight edges 4 and with a continuous compoundly-curved inner edge 5. This continuous compoundly-curved inner edge 5 is provided with a concaved sharply-curved portion 6, contiguous to the outer end 45 of the short arm 3, a long concaved curved portion 7, extending nearly the full length of the long arm 2 and merging at one end into the aforesaid sharply-curved portion 6. In 50 addition to the said curved portions 5 and 6 the said continuous compoundly-curved inner edge is also provided with a convexed nearly-angular lobe 8, directly adjoining the outer end of the long arm 2 and merging directly into and forming a continuation of the aforesaid long curve 7.

What is claimed is—

The design for the tailors' square and scroll herein shown and described. 60

In testimony that I claim the foregoing as my own I have hereto affixed my signature in the presence of two witnesses.

LILLIAN A. EGGLESTON.
